(57) **CLAIM**

The ornamental design for a measuring scale, as shown, and described.

DESCRIPTION

FIG. 1 is a perspective view of a measuring scale;
FIG. 2 is a top plan view thereof;
FIG. 3 is a bottom plan view thereof;
FIG. 4 is a right elevation view thereof, the left elevation view being a mirror image thereof;
FIG. 5 is a front view thereof; and,
FIG. 6 is a rear view thereof.

The broken lines represent unclaimed matter and form no part of the claimed design.
